Patty Chidiac; Mark W. Croll(57) **CLAIM**

The ornamental design for a fastener driving tool housing, as shown and described.

DESCRIPTION

FIG. 1 is a front perspective view of the fastener driving tool housing showing my new design;
 FIG. 2 is a right side view of same;
 FIG. 3 is a left side view of same;
 FIG. 4 is a front view of the present tool housing;
 FIG. 5 is a rear view of same;
 FIG. 6 is a top view of the fastener driving tool housing; and,
 FIG. 7 is a bottom view of the same.
 The structure shown in broken lines is for environment purposes only and does not form part of the claimed invention.
